UNITED STATES PATENT OFFICE

141,802

DESIGN FOR A SUCTION CLEANER DUSTING BRUSH OR SIMILAR ARTICLE

Kurt H. Wittke, Berkeley, Mich., assignor to
Eureka Vacuum Cleaner Company, Detroit,
Mich., a corporation of Michigan

Application November 11, 1944, Serial No. 116,274

Term of patent 14 years

(Cl. D9—2)

To all whom it may concern:

Be it known that Kurt H. Wittke, a citizen of the United States of America and a resident of Berkeley, in the county of Oakland and State of Michigan, has invented a certain new, original, and ornamental Design for a Suction Cleaner Dusting Brush or Similar Article, of which the following is a specification, reference being had to the accompanying drawing, forming a part thereof, and wherein:

Fig. 1 is a plan view of a suction cleaner dusting brush or similar article embodying my design.

Fig. 2 is a side elevational view of the same; and Fig. 3 is a front elevational view of the same.

I claim:

The ornamental design for a suction cleaner dusting brush or similar article, as shown.

KURT H. WITTKE.
